Primary Examiner — John A Voytek(74) *Attorney, Agent, or Firm* — Thorpe North & Western(57) **CLAIM**

The ornamental design for an automobile tire, as shown and described.

DESCRIPTION

FIG. 1 is a perspective view of an automobile tire showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged fragmental view thereof; taken along lines 8-8 in FIG. 2; and,

FIG. 9 is a cross-sectional view thereof; taken along lines 9-9 in FIG. 8.

The broken lines in the drawings are for the purpose of illustrating unclaimed portions of the automobile tire and form no part of the claimed design, and the dash-dot-dash broken lines illustrate the boundary of the claimed design.
